(57) **CLAIM**

The ornamental design for a slider of zip fasteners as shown and described.

DESCRIPTION

The patent or application file contains at least one drawing executed in color. Copies of this patent or patent application publication with color drawing(s) will be provided by the Office upon request and payment of the necessary fee.

1. Slider of zip fasteners

Fig. 1.1 is a front elevational view of a slider of zip fasteners showing the new design;

Fig. 1.2 is a rear elevational view thereof;

Fig. 1.3 is a left side elevational view thereof;

Fig. 1.4 is a right side elevational view thereof;

Fig. 1.5 is a top plan view thereof;

Fig. 1.6 is a bottom plan view thereof; and

Fig. 1.7 is a top, rear and right side perspective view thereof.
